DESIGN FOR A COMBINED CAMERA SUPPORT AND FLOODLIGHT LAMP HOLDER

Abraham Secofsky and Murray A. Meisel, New York, and Alexander Zalman, Kew Gardens Hills, N. Y.

Application December 20, 1948, Serial No. 150,272

Term of patent 14 years

(Cl. D61—1)

To all whom it may concern:

Be it known that we, Abraham Secofsky, Murray A. Meisel, and Alexander Zalman, all citizens of the United States and residing respectively at New York city, in the county of Kings and State of New York, at New York city, in the county of Kings and State of New York, and at Kew Gardens Hills, in the county of Queens and State of New York, have invented a new, original, and ornamental Design for a Combined Camera Support and Floodlight Lamp Holder, of which the following is a specification, reference being had to the accompanying drawing, forming a part thereof.

Fig. 1 is a front elevational view of a combined camera support and floodlight lamp holder, showing our new design.

Fig. 2 is a top plan view thereof.

Fig. 3 is a bottom plan view thereof.

Fig. 4 is a rear elevational view thereof.

Fig. 5 is a vertical sectional view taken on line 5—5 of Fig. 1.

The parts shown in broken lines in Figs. 2, 3, and 4 are to be finished in full lines like the corresponding parts in Fig. 1.

We claim:

The ornamental design for a combined camera support and floodlight lamp holder, substantially as shown and described.

ABRAHAM SECOFSKY.
